FIG. 1 is a front elevational view of a light standard or similar article illustrating my new design.

FIG. 2 is an enlarged cross-sectional view taken on line 2—2 of FIG. 1.

FIG. 3 is an enlarged cross-sectional view taken on line 3—3 of FIG. 1.

FIG. 4 is a rear elevational view of the second embodiment of my design.

FIG. 5 is a front elevational view thereof.

FIG. 6 is an enlarged top plan view thereof.

FIG. 7 is an enlarged cross-sectional view taken on line 7—7 of FIG. 4.

FIGS. 8 and 9 are enlarged cross-sectional views of further embodiments of my design, the cross-sections being taken on planes identical to lines 7—7 in FIG. 4, it being understood that the embodiments differ from FIG. 4 only in cross-section.

The lamps are shown in broken lines in FIGS. 1, 4, 5 and 6 for illustrative purposes only.

I claim:

The ornamental design of a light standard or similar article, as shown and described.
